FIBER TUBE ROLLING MACHINE

Homer J. Davis, Wilmington, Del.

Application September 2, 1930, Serial No. 479,378

59 Claims. (CL. 93—83)

This invention relates to a tube rolling machine and more particularly to an automatic fiber tube rolling machine wherein is combined a plurality of mechanisms correlated and timed to automatically deliver a tube from a magazine and pass the same back and forth through companion rolls to finish and remove same from its mandrel or supporting rod.

The primary object of the invention is a design of machine that will quickly and efficiently direct the fiber tubes back and forth between the finishing rolls and at time intervals give partial turning movements to the tubes to accomplish a uniform finishing action upon the entire outer surface of the tubes.

An object of the invention resides in the novel design and correlation of the companion mechanisms whereby the number of passes that the tube makes between the finishing rolls through a particular groove may be accurately regulated and changed at will with the change-over from one groove of the rolls to another groove accurately timed.

Another object of the invention is the provision of a machine that will subject a group of tubes to reciprocatory movements, periodically turn the tubes to obtain uniform action and automatically discharge the same as finished.

Another object of the invention relates to the adjustability of the machine for accommodating different lengths of tubes and tubes of various diameters.

A still further object of the invention is the novel design and construction of each of the correlated mechanisms, a complete unit within themselves and capable of adaptation with other types of machines.

A feature of the invention resides in the novel construction of the heads for gripping and carrying a group of tubes in their reciprocatory movements and capable of giving turning movements to the tubes at required intervals in the reciprocatory travel thereof.

Besides the above my invention is distinguished in the novel design of the manually set controls whereby the number of passages of a tube through a predetermined groove can be determined in advance the time interval of partial turning of the tube determined in advance and the distance of travel of the tubes in their reciprocatory movements determined in advance.

With these and other objects in view the invention will be better understood from the following detailed description taken in connection with the accompanying drawings wherein—

Figure 1 is a side elevation of the machine with parts broken away.

Figure 2 is a top plan view with parts removed.

Figure 3 is an end elevation looking toward the left hand end of the machine illustrated in Figure 1.

Figure 17 is a cross sectional view adjacent the stop device.

Figure 18 is a vertical sectional view of the left head.

Figure 19 is a cross sectional view of the machine adjacent one of the feeding mechanisms.

Figure 20 is a longitudinal sectional view of the drive mechanism.

Figure 20a is a detailed sectional view of one end portion of the drive mechanism.

Figure 21 is a horizontal sectional view of a portion of the drive mechanism.

Broadly stated, my invention consists of a supporting frame upon which is mounted delivery mechanism which in turn is directly associated with duplex feeding mechanisms mounted for reciprocatory movements upon the supporting frame. These latter mechanisms are operated by a novel type of drive mechanism operated directly off of a prime mover such as a motor through loose and fast pulleys. This driving mechanism includes a novel type of time mechanism. The machine is completed by inter-relating with the foregoing mechanisms rolling mechanism illustrated as companion rolls having 50

in their peripheral surfaces a plurality of companion grooves.

Supporting frame

- 5 Numeral 1 designates the supporting frame of the machine consisting of the bed 2 and the legs 3.

Rolling mechanism

10 The rolling mechanism in this particular instance is illustrated as companion rolls 4 and 5, the peripheral surfaces of which are provided with a plurality of companion grooves 6 of varying depths so as to subject a tube passing therethrough to progressive contracting actions in a 15 radial direction with relation to the travel of the tube. This action produces a smooth exterior surface and somewhat elongates the tube and besides releases same from its adhering contact with the mandril or supporting rod. As is well 20 known in the art, fiber tubes are produced by winding a chemically treated length of paper upon a metal rod or mandril and finally drying the tube which causes the same to tightly adhere to the rod. Heretofore the tubes were manually removed from the rod by the manual operation of 25 passing the tube back and forth between the rolls of a rolling mill until the tube was completely finished and loosened from the rod, after which the rod was manually forced from the tube by the operator. As heretofore stated, the 30 main object of my invention is to pass the tube back and forth through the rolling mill mechanically, subjecting the tubes in their reciprocatory movements to a partial turning action to assure 35 the accomplishment of a uniform action and removal of the tube from its rod.

40 The companion rolls 4 and 5 have a gear connection with each other as indicated at 7, the gear connection being operated directly off a gear train 8 that has a drive connection with a drive shaft 9. A gear train 8b operated off of the gear connection 7 includes a friction gear 10 having an operative engagement with the driving connection hereinafter set forth. The drive shaft 9 45 has mounted thereon companion driven gears 11 and 12 each carrying a clutch member 13 co-operating with a clutch collar 14 splined upon the drive shaft for selective movements into engagement with said members 13 so as to selectively drive the driven gears 11 and 12 from the drive shaft 9. The clutch collar 14 has a sliding 50 operative connection with a shift lever 15 pivoted at an intermediate point as indicated at 16 and having a forked end 17 engaging the manipulating rod 18. This rod 18 is slidably supported by a plate 19 provided with depressions 20 for selective engagement with a projection 21 on the end of the lever for mechanically holding the lever in either one of its two positions when shifted. 55 Mounted on the manipulating rod 18 are companion springs 22 abutting the shift lever so as to accomplish a more effective movement of the manipulating lever when the latter is periodically reciprocated in a manner hereinafter set forth. 60

65 Interconnected to the manipulating rod 18 is a bell crank lever 23 which in turn has a pivotal connection 24 with the driving mechanism hereinafter described.

70 The driven gears 11 and 12 are loose upon the drive shaft and are in constant mesh with drive gears 25 and 26, mounted upon a drive shaft 27 that carries the drive pulley 28.

75 With the mechanism just described it will be appreciated that the grooved rolls 4 and 5 may be driven in opposite directions, to draw an object

therebetween by the shifting of the clutch collar 14 which is accomplished automatically in the operation of the machine as hereinafter set forth.

Delivery mechanism

5

The delivery mechanism comprises a magazine, support table or hopper 29 of skeleton construction, in which a stock of tubes are placed for automatic feeding, one at a time, into operative relation with the duplex feeding mechanisms 10 of my improved machine. This magazine 29 discharges on to runways 30 for directing the travel 15 of the tube into operative engagement with the duplex feeding mechanisms.

For the purpose of automatically delivering 15 the tubes one at a time from the delivery mechanism in time relation with the travel of the companion mechanisms of the machine I have illustrated a novel form of discharging means 20 consisting of companion triggers 32 fixed to an operating shaft 33 supported by the magazine. These triggers 32 are provided with bills 34 directly related with the first tube so that in the swinging of the trigger, accomplished in a manner hereinafter set forth, the first tube will be 25 elevated and discharged from the magazine and the succeeding tube held against movement until the trigger returns to normal position which enables the next tube to feed by gravitational action into position so that the tube that has assumed the first position may be raised by another 30 operation of the trigger. Secured to the shaft 33 is an arm 35 having a pivotal connection with the link 36 that is connected to a second arm 37, loosely mounted on a fixed rod 38 supported by 35 the frame of the machine. Arranged in parallel relation with the rod 38 is the actuating rod 39 operated in a novel manner as hereinafter set forth and having directly secured thereto an arm 40 that in turn has a pivotal connection with 40 the link 41 which also has a pivotal connection with the arm 37.

45 As far as I have proceeded it will be appreciated that in the movement of rod 39 the arm 37 will be swung in a predetermined direction for 45 transmitting motion to shaft 33 through the arm 35 and link 36. The operation of shaft 33 will swing the trigger upwardly thereby displacing the first tube so that the same may run along the runways into operative engagement with the 50 companion feed mechanisms of the machine, the trigger holding the succeeding tubes against displacement until the trigger returns to normal position which is accomplished when the shaft 39 is returned to normal position.

55 The released tube in reaching its final position upon the runways engages a support 42 which is designed to be displaced horizontally when the rod 39 is operated. To accomplish this desired result the support is provided with a bracket 43 having a swinging connection with the arms 37 and 40 and supporting a grooved roller 44, the 60 grooves of which are adapted to align with the grooves in the rolls 4 and 5. I wish to call attention to the fact that the grooves of the roll 44 65 are adapted to be shifted into alignment with different sets of grooves in the companion rolls 4 and 5 so that tubes as supported by the grooved roll 44 may be first passed through one set of grooves of the companion rolls 4 and 5 and then 70 through another set of grooves of the rolls 4 and 5 for the purpose hereinafter set forth.

Duplex feeding mechanisms

75 The duplex feeding mechanisms include co-

operatively operating heads hereinafter known as a "left" head 45 and a "right" head 46, the former reciprocating the tubes towards the companion rolls 4 and 5 in a right hand direction whereas the latter reciprocates the tubes through the rolls 4 and 5 in a left hand direction thereby enabling the tubes to be rapidly subjected to horizontal reciprocatory movements in their passage through the rolls 4 and 5.

10 As the companion heads 45 and 46 are of similar construction I will limit my description to the details of the "left" head designated by the numeral 45.

Each head consists of companion arms 47 and 48, the former loosely mounted on the rod 38 and the latter fixed to the rod 39 so as to be given swinging movement in the oscillatory movements of the rod 39. A main link 49 provided with tube guiding holes 49b is pivotally connected to the arms so that the arms will swing in unison in the oscillatory movements of the rod 39. Pivotally connected to the arms 47 and 48 are the auxiliary arms 50 and 51, these auxiliary arms having their intermediate portions connected to the arms 47 and 48 so that the opposite ends of the auxiliary arms may be free to swing in an arc of a circle. The lower ends of the auxiliary arms 50 and 51 are pivotally connected together by a secondary link 52 that has directly bolted thereto as indicated at 53 the lower jaw element 54 of the tube or rod gripper 55. The upper gripping element of the rod gripper 55 is illustrated as a plurality of individual jaws 56 slidably mounted in the cross bar 57 that has its ends pivotally connected to the upper end of the auxiliary arms 50 and 51. Each individual jaw 56 is yieldingly pressed toward the lower jaw element 54 by a spring 58 engaging a collar 59 on the stem 60 of the jaw and engaging under the cross bar 57. Mounted on the stem 60 are clamp nuts 61 which control resilient action of the jaws.

As far as I have proceeded it will be appreciated that in the swinging movements of the arms 47 and 48 the rod grip 55 can be displaced laterally for displacing the tubes laterally as a group for changing the relation of the grooves of the rolls 4 and 5 that are engaging the tubes. It will be noted that when the auxiliary arms 50 and 51 are swung upon the main arms 47 and 48 the cross bar and the secondary links will be reciprocated in opposite directions in relation to each other thereby giving corresponding movements to the lower jaw element and the individual jaws which accomplishes a partial rotation of the rods or tubes engaged by the jaws. It is my desire to have the various parts of the heads so designed that in the movement thereof the tubes will be given a quarter turn individually and may be shifted as a group horizontally for changing relative arrangement of the tubes and the grooves in the rolls 4 and 5.

For the purpose of accomplishing shifting of the auxiliary arms 50 and 51 automatically I have mounted upon the secondary link 52 a cam roller 62 adapted at the required intervals to engage two cams 71 and 72 upon the bed of the machine, each illustrated as an arm 65 having a cam shaped extremity 64. Attention is called to the fact that each arm 65 is pivotally connected to the bed 2 at the point 63 so as to swing in a horizontal plane, a spring 66 urging the arm 65 to a normal position after the same has been displaced by the head due to the fact that tubes have not been completely received by the rolls 4 and

5 or the head has been shifted laterally by the shifting mechanism hereinbefore set forth.

For the purpose of shifting the rod grip 55 laterally for changing the aligning position of the tubes with the grooves in the rolls 4 and 5 I have provided the main arms 47 and 48 with a cam roller 67 on a connecting link 67b adapted to engage a second cam arm 68 provided with a cam shaped extremity 69. For the purpose of returning the jaw elements of the gripper to normal position after the same has been shifted by the cam arm 68 I have illustrated the cam arm 71 in horizontal alignment with the cam arm 68 so as to engage the cam roller 67 when the head has moved its required distance towards the rolls 4 and 5. When the cam roller 67 strikes cam arm 71 the spring 66 will give until the tubes have been fed from the head by the action of the rolls 4 and 5 after which the spring will react to force the arm 71 to normal position and with it the companion parts of the head.

As far as I have proceeded it will be appreciated that the tube in moving down the runway will be brought in horizontal alignment with the gripper device of the "left" head so that in the forward movement of the head the ends of the rods upon which the tubes are mounted are gripped and moved in a horizontal direction until engaged by the grooves of the rolls 4 and 5. When this has been accomplished the rolls 4 and 5 feed the tubes horizontally until engaged by the "right" head. As the driving mechanism of the machine hereinafter described is operated in unison with the rotation of the rolls 4 and 5 it will be appreciated that just as soon as the ends of the rods upon which the tubes are mounted are engaged by the "right" head the drive mechanism will drive the "right" head in a right hand direction. The "right" head will continue to travel until its cam roller is engaged by a cam lever 73 similar to the cam lever heretofore described for shifting the jaw elements to give a partial turn to the tubes. After this has been accomplished the driving mechanism of the machine will reverse for again moving the tubes into engagement with the rolls 4 and 5. As the tubes leave the "right" head a cam 73b engaging the cam roller of the head will return the jaws of the head to normal position. As the tubes pass through the rolls 4 and 5 they will be again gripped by the "left" head and carried forwardly until the head reaches its normal position whereupon the tubes are again given a quarter of a turn and passed back to the rolls 4 and 5. As set forth, the "left" head at stated intervals is shifted laterally for displacing the position of the tubes as a group in relation to the grooves of the rolls 4 and 5 so that the tubes will be passed through a new set of grooves for varying the action of the rolls 4 and 5 upon the tubes.

Arranged at the right hand end of the machine as illustrated in the drawings is an adjustably mounted stop plate 74 positioned to engage the ends of the rods 75 upon which the tubes 76 are formed so as to properly align the rods.

Drive mechanism

The drive mechanism consists of a catch 77 slidably supported by each head and designed to have a stem 78 and a bill 79 that is provided with a cam surface 80. A spring 81 is arranged to constantly urge the jaw toward operative engagement with a rack bar 82 that is directly engaged by the friction gear 10.

The bill 79 is adapted to enter notch 83 in the

rack bar so that the catch and with it the head may be carried along with the rack bar and to prevent dis-engagement of the catch with the rack bar when moving therewith I have arranged 5 the stem 78 in sliding relation with the inner wall 84 of the frame of the machine and engageable with the notch 85 in the frame when the dog has been moved to its normal position. As far as I have proceeded it will be appreciated that the 10 inner engagement of the cam surface of the bill 79 with the rack bar will mechanically force the stem of the catch into engagement with the notch 85 when brought into registration therewith thereby disconnecting the head from the rack bar 15 and enable the same to continue its movement for engagement with the opposite head. Attention is called to the fact that the pressure of the engagement between the cam surface 80 and the rack bar 82 is slightly greater than the tension of the spring 81 so that the catch will be forced into the notch 85 when the catch reaches a position in registration with the notch 85.

The rack bar 82 is slidably mounted in a tube 86 of rectangular configuration and fixed to the 25 frame of the machine as shown in Figure 20. This tube 86 has slidably mounted on the opposite ends thereof a pair of brackets 87 and 88 that are connected together by a clutch rod 89 carrying a block 90 that has a pin and slot connection 91 with the bell crank lever 23. It will be noted that upon reciprocation of the clutch rod 30 89 the clutch mechanism through the bell crank lever 23 will be shifted alternately in opposite directions for alternately changing the direction of travel of the operating mechanism.

To accomplish the proper sliding action of the brackets 87 and 88 in time relation with the operating mechanism each bracket is provided with a dog 92 which is adapted to gravitate into operative engagement with a notch 93 in the rack bar 82 when the latter has traveled a predetermined distance. In other words, when the rack bar is about to complete its travel in either direction the notch 93 operatively receives the dog 45 92 for giving about one-half inch travel to the block 90 which through the mechanism heretofore described manipulates the clutch device for reversing the direction of travel of the rack bar 82. Simultaneous with this action a timing mechanism is set into operation for timing the 50 number of passages of a tube through a particular groove of the rolls 4 and 5.

The timing mechanism consists of an arm 94 fixed to the rod 89 and carrying a pawl 95 co-operatively associated with the rack bar 96. This 55 rack bar 96 carries a head 97 related with a pin 98 that is slidably mounted in the support 99 carried by the frame of the machine. The pin 98 is urged outwardly by a spring 100, the head 97 forcing the pin inwardly against the action of the spring when the rack bar 96 is manipulated by the pawl 95. A locking pawl 101 also engages the rack bar 96 to lock the same in its various positions when manipulated by the pawl 95.

60 Co-operatively associated with the head 97 is the set screw 102 of a setting device 103 which includes a block 104 slidably mounted on the support 99 through the means of a projection 105 that carries notches 106 associated with the catch 107 for adjusting the position of the set screw in relation to the head 97. Thus it will be appreciated that adjusting the set screw 102 will fix the extent of movement of the head 97 as 65 acted upon by the spring 108. As the head 97 directly engages the pin 98 it will be understood

that the extent of travel of pin 98 is controlled by the movement of the rack bar. Fixed to the oscillating rod 39 is the lever 109 carrying a weight 110 which when the lever is released in a manner hereinafter described forces the lever downwardly and thereby turns the rod 39. This lever 109 has an arm 109b normally resting upon the pin 98 and thus it will be appreciated that when the pin has been fully retracted within its support the lever will be free to gravitate for giving 10 turning movement to the rod 39 for the accomplishment of objectives heretofore set forth. The pawls 95 and 101 are provided with projections 111 and 112 positioned directly under the weighted lever 109 so that in the downward 15 movement thereof both pawls will be released from the rack bar for enabling the rack bar to return, through the action of the spring 108, to a normal position fixed by the setting of the set screw 102.

Complete cycle of operation

Assuming that the clutch collar 14 is in engagement with driven gear 11, setting into operation drive shaft 21 will cause the driven shaft 25 9 to rotate in a predetermined direction which through the train of gear rotates the rolls 4 and 5 in a predetermined direction. Simultaneous with this action the friction gear 10 is giving a sliding movement to the rack bar 82. Assuming 30 that rack bar 82 is traveling from the left to the right, the left hand notch 83 will receive the bill 79 of the catch of the left head with the result that the left head is moved towards the rolls 4 and 5. This motion of the left head will continue until the catch 77 is forced into another notch 85 positioned in the frame 1 contiguous to the rolls 4 and 5 by the co-action of the inclined surface 80 of the bill 79 and the inclined surface 40 of the notch 85. This action causes dis-engagement between the catch 77 and the rack bar 82 with the result that further movement of the head is arrested without interfering with further movement of the rack bar. This allows the rack bar to continue its travel for bringing about 45 an engagement thereof with the catch 71 of the right head for causing the same to travel from its position contiguous to the rolls 4 and 5 towards the right end of the machine. When the right head has travelled its limited distance to the 50 right, dis-engagement is accomplished between its catch and the rack bar for arresting further movement of the right head by the rack bar.

Simultaneously with this action the bracket 87 is given a slight sliding movement by interengagement of the pawl 92 with the notch in the 55 rack bar which causes the shifting of the bell crank lever 23 and the clutch mechanism for reversing the direction of travel of the drive mechanism.

As the left head approaches its extreme right position the cam roller 67 engages cam 71 for displacing the jaw gripping elements laterally in relation to each other for giving a partial turn to the rods engaged thereby. In the final movement of the left head the cam roller 62 will engage the second cam 69 with the result that the arms 47 and 48 will be returned to their normal vertical position after having been previously thrown to an inclined position by the timing 70 mechanism hereinbefore described. It is understood that in the movement of the left head to its extreme right position the cam roller 67 will engage the cam 71 for returning the gripping jaws to their normal position, the spring 72 delaying 75

this action until the tube rods have completely left the head by the drawing action of the rolls 4 and 5. Attention is called to the fact that the cams 73 and 73b at the right of the machine are used solely for the purpose of shifting the position of the gripper jaws back and forth for giving partial turning movements to the tube rods, whereas the additional cam 69 at the left of the machine is utilized for returning the 10 tire head to its vertical upright position after the same has been displaced laterally by the timing mechanism for changing the relative position of the tube rods and the grooves of the rolls 4 and 5.

In the movement of the clutch rod 89 for shifting the direction of travel of the operating mechanism the rack bar 96 is operated by the pawl 95 and thus it will be appreciated that in each shifting of the clutch mechanism the rack bar is moved for changing its position relative to 20 the weighted lever 109 so that at the proper time the pin 98 will be dis-engaged with the arm 109b for allowing the lever to drop and thereby turn the rod 39 for giving heretofore stated lateral displacement movements to the heads for changing the relative alignment of the tube rods with 25 the grooves of the rolls 4 and 5. With the component parts of the timing mechanism and left head in the position just mentioned, the left head travels to the left until the cam arm 69 engages the cam roller 67 for throwing the entire head into normal upright vertical position for again receiving the group of tubes that are passing through the rollers 4 and 5.

In the shifting of the rod 39 the triggers 32 are 35 operated for swinging the bills 34 upwardly for discharging a tube onto the runways for travel into engagement with the left traveling head. Thus it will be appreciated that one tube at a time is passed to the traveling heads in timed 40 relation with the travel of the heads so that the rods may be engaged one at a time by the traveling heads as the tubes one at a time are being discharged, a group of tubes being supported by the traveling heads at all times during the operation 45 of the machine. Each tube in leaving the last groove of the rolls 4 and 5 is discharged to one side of the traveling "left" head with the result that the same may gravitate from operative engagement with the heads into a suitable 50 receptacle.

Of course it is to be understood that the capacity of the machine can be considerably increased by varying the size of the heads and the number of tubes that may be supported thereby.

Of course it is to be understood that the component mechanisms may be designed and arranged in other relations than illustrated and the various elements of the associated mechanisms may be constructed in other ways than illustrated and therefore I am not attempting to protect in this parent application the mechanical details of the component parts but the basic features consisting of grouping together a plurality of novel mechanisms in a new relation for the accomplishment of new results. Therefore I do not desire to be limited in protection in any manner whatsoever except as set forth in the following claims.

What I claim is:

1. A fiber tube rolling machine comprising a supporting frame, rolling mechanism mounted thereon, delivery mechanism, feeding mechanism for receiving the tubes from the delivery mechanism and reciprocating the same through said rolling mechanism, and timing mechanism for

timing the number of passages of the tubes through the rolling mechanism.

2. A fiber tube rolling machine comprising a supporting frame, rolling mechanism mounted thereon, delivery mechanism duplex feeding mechanisms on opposite sides of said rolling mechanism for receiving tubes from the delivery mechanism and reciprocate the same through said rolling mechanism, drive mechanism for operating the duplex feeding mechanisms and timing mechanism controlling the number of passages of the tubes through said rolling mechanism.

3. A fiber tube rolling machine comprising a supporting frame, rolling mechanism mounted thereon, delivery mechanism, duplex feeding mechanisms on opposite sides of said rolling mechanism for receiving tubes from the delivery mechanism and reciprocate the same through said rolling mechanism, drive mechanism for operating the duplex feeding mechanisms, timing mechanism controlling the number of passages of the tubes through said rolling mechanism, and mechanism for partially turning the tubes during the reciprocatory movements thereof.

4. A fiber tube rolling machine comprising rolling mechanism, feeding mechanism for feeding tubes back and forth through the rolling mechanism and mechanism for timing the number of passages of the tubes through the rolling mechanism.

5. A fiber tube rolling machine comprising rolling mechanism, feeding mechanism for feeding tubes back and forth through the rolling mechanism, mechanism for timing the number of passages of the tubes through the rolling mechanism, and mechanism for giving turning motion to the tubes after a predetermined number of passages through said rolling mechanism.

6. A fiber tube rolling machine comprising rolling mechanism, feeding mechanism for passing tubes back and forth through the rolling mechanism, timing mechanism for determining the number of passages of the tubes through the rolling mechanism, and turning mechanism operatively related with the feeding mechanism for giving partial rotations to the tubes.

7. A fiber tube rolling machine comprising a supporting frame, rolling mechanism mounted thereon, reversible drive mechanism for the rolling mechanism, duplex feeding mechanisms operated by the said drive mechanism for feeding tubes back and forth through the rolling mechanism, and timing mechanism controlling the number of passages of the tubes through the rolling mechanism by said feeding mechanisms.

8. A fiber tube rolling machine comprising a supporting frame, rolling mechanism mounted thereon, reversible drive mechanism for the rolling mechanism, duplex feeding mechanisms operated by the said drive mechanism for feeding tubes back and forth through the rolling mechanism, timing mechanism controlling the number of passages of the tubes through the rolling mechanism by said feeding mechanisms, and means for giving partial turns to the tubes after a predetermined number of passages through said rolling mechanism.

9. A fiber tube rolling machine comprising a supporting frame, rolling mechanism mounted thereon, reversible drive mechanism for the rolling mechanism, duplex feeding mechanisms operated by the said drive mechanism for feeding tubes back and forth through the rolling mechanism, timing mechanism controlling the number of passages of the tubes through the rolling mechanism, timing mechanism controlling the num-

ber of passages of the tubes through the rolling mechanism by said feeding mechanisms, means for giving partial turns to the tubes after a predetermined number of passages through said rolling mechanism, and discharge the tubes to one side of said rolling mechanism.

10. A fiber tube rolling machine comprising in combination a pair of rolls having a plurality of aligning grooves in the peripheral surface thereof, duplex feeding mechanism for feeding tubes back and forth through said grooves, and timing mechanism for shifting the relation of the tubes and said grooves.

15. A fiber tube rolling machine comprising in combination a pair of rolls having a plurality of aligning grooves in the peripheral surface thereof, duplex feeding mechanism for feeding tubes back and forth through said grooves, timing mechanism for shifting the relation of the tubes and 20 said grooves, and means for giving a partial turn to the tubes before their passage through said grooves.

25. A fiber tube rolling machine comprising in combination a pair of rolls having a set of grooves in their peripheral surfaces, duplex feeding mechanisms feeding a tube through the first groove, timing mechanism co-operating with the feeding mechanisms for shifting the tube progressively into engagement with the grooves of the rolls, 30 until discharged from the machine as leaving the last groove in the rolls.

35. A fiber tube rolling machine comprising a pair of rolls each having in its peripheral surface horizontally aligned grooves, the grooves of one roll having a matching relation with the grooves of the other roll, mechanism for selectively passing a tube through said grooves progressively, and mechanism for timing the number of passages of the tube through any one particular 40 groove.

45. A fiber tube rolling machine comprising a pair of rolls each having in its peripheral surface horizontally aligned grooves, the grooves of one roll having a matching relation with the grooves of the other roll, mechanism for selectively passing a tube through said grooves progressively, mechanism for timing the number of passages of the tube through any one particular groove, and means for giving a partial turn to the tube 50 before its passage through said grooves.

55. A fiber tube rolling machine comprising a pair of rolls each having in its peripheral surface horizontally aligned grooves, the grooves of one roll having a matching relation with the grooves of the other roll, mechanism for selectively passing a tube through said grooves progressively, mechanism for timing the number of passages of the tube through any one particular groove, means for giving a partial turn to the tube before its 60 passage through said grooves, the last grooves of said rolls discharging the tube from the machine.

65. A fiber tube rolling machine comprising rolling mechanism, duplex feeding mechanisms including companion grippers for gripping the tubes and reciprocating the same through said rolling mechanism, and timing mechanism operating on said grippers to shift the same laterally for changing the position of the tubes with 70 relation to said rolling mechanisms.

75. A fiber tube rolling machine comprising rolling mechanism, duplex feeding mechanisms including companion grippers for gripping the tubes and reciprocating the same through said rolling mechanism, timing mechanism operating

on said grippers to shift the same laterally for changing the position of the tubes with relation to said rolling mechanisms, and mechanisms co-operating with said timing mechanism for periodically giving turning movements to the tubes.

10. A fiber tube rolling machine comprising rolling mechanism, means for driving said mechanism in opposite directions, feeding mechanism for feeding tubes to either side of said rolling mechanism thereby giving reciprocatory movements to the tubes, manually set mechanism for determining the number of passages of tubes through said rolling mechanism, and mechanism for periodically turning the tubes in their reciprocatory movements.

15. A fiber tube rolling machine comprising rolling mechanism, a pair of companion slidably mounted feed mechanisms disposed respectively on opposite sides of said rolling mechanism, drive mechanism periodically engaging said feed mechanisms to slide the same according to the travel of said rolling mechanism, and means for discharging a tube from the rolling mechanism as completed.

20. A fiber tube rolling machine comprising rolling mechanism, reversible drive mechanism, a pair of companion feeding heads for feeding tubes back and forth through said rolling mechanism, and a control connection between said heads and said drive mechanism whereby said drive mechanism is reversed in the movements of the said heads towards and away from the rolling mechanism.

25. A fiber tube rolling machine comprising rolling mechanism, reversible drive mechanism for operating said rolling mechanism, a pair of companion feeding heads for feeding tubes back and forth through said rolling mechanism, a control connection between said heads and said drive mechanism whereby said drive mechanism is reversed in the movements of the said heads towards and away from the rolling mechanism, and timing mechanism set into operation according to the position of said heads for displacing the latter in a direction axially of the rolling 40 mechanism.

30. A fiber tube rolling machine comprising a pair of rolls, reversible drive mechanism therefor, a pair of tube supporting heads operated directly off said drive mechanism for movements 50 toward and away from said rolls.

35. A fiber tube rolling machine comprising a pair of rolls, reversible drive mechanism therefor, a pair of tube supporting heads operated directly off said drive mechanism for movements 55 toward and away from said rolls, and control mechanism between said heads and said drive mechanism whereby the direction of travel of said drive mechanism may be changed according to the position of said heads.

40. A fiber tube rolling machine comprising a pair of rolls, reversible drive mechanism therefor, a pair of tube supporting heads operated directly off said drive mechanism for movements 60 toward and away from said rolls, control mechanism between said heads and said drive mechanism whereby the direction of travel of said drive mechanism may be changed according to the position of said heads, and timing mechanism 70 for giving displaceable movement to said heads relative to said rolls according to the position of the heads in relation to the rolls.

45. A fiber tube rolling machine comprising a pair of rolls, a pair of slidably mounted heads 75

for feeding-work toward and away from said rolls, drive mechanism for reversibly driving said rolls and periodically sliding said heads.

26. A fiber tube rolling machine comprising a pair of rolls, a pair of slidably mounted heads for feeding-work toward and away from said rolls, drive mechanism for reversibly driving said rolls and periodically sliding said heads, and a control device set into operation according to the position of said heads for reversing the direction of travel of said drive mechanism.

27. A fiber tube rolling machine comprising a pair of rolls, a pair of slidably mounted heads for feeding-work toward and away from said rolls, drive mechanism for reversibly driving said rolls and periodically sliding said heads, a control device set into operation according to the position of said heads for reversing the direction of travel of said drive mechanism, and means for shifting one of said heads in a direction longitudinally of said rolls at predetermined points in the travel of said heads.

28. A fiber tube rolling machine comprising a frame, a pair of rolls mounted thereon, drive mechanism for the rolls, a pair of work supporting heads slidably mounted on the frame for movements toward and away from said rolls, means periodically connecting said heads to said drive mechanism to be operated thereby, and an automatic connection between said heads and said drive mechanism whereby the direction of travel of the latter may be changed.

29. A fiber tube rolling machine comprising a rolling device, a pair of work-engaging heads mounted for sliding movements toward and away from said device for feeding-work therethrough, reversible drive mechanism for said device, means for periodically driving said heads from said drive mechanism, and means for shifting the path of travel of said heads in relation to said rolling device.

30. A fiber tube rolling machine comprising a frame, companion rolls mounted upon said frame, reversible drive mechanism for said rolls, a pair of work-heads slidably mounted on said frame for movements toward and away from said rolls, and an aligning device supported by said frame for periodically aligning the work with said rolls as reciprocated by said heads.

31. A fiber tube rolling machine comprising a frame, companion rolls mounted upon said frame, reversible drive mechanism for said rolls, a pair of work-heads slidably mounted on said frame for movements toward and away from said rolls, an aligning device supported by said frame for periodically aligning the work with said rolls as reciprocated by said heads, and means for periodically connecting said heads to said drive mechanism for the reciprocating thereof.

32. A fiber tube rolling machine comprising a frame, companion rolls mounted upon said frame, reversible drive mechanism for said rolls, a pair of work-heads slidably mounted on said frame for movements toward and away from said rolls, an aligning device supported by said frame for periodically aligning the work with said rolls as reciprocated by said heads, means for periodically connecting said heads to said drive mechanism for the reciprocating thereof, and means for periodically turning the work within the heads in the reciprocatory movements of the latter.

33. A fiber tube rolling machine comprising a frame, a pair of grooved rolls, mounted on said frame, a pair of co-operating work-engaging

heads slidably mounted on said frame for movement toward and away from said rolls and each including companion gripping elements, reversible drive mechanism for operating said rolls and periodically reciprocating said heads and spaced devices engaging periodically with said gripping elements for shifting the same laterally in the movement towards and away from said rolls for turning work supported thereby.

34. A fiber tube rolling machine comprising a frame, a pair of grooved rolls, mounted on said frame, a pair of co-operating work-engaging heads slidably mounted on said frame for movement toward and away from said rolls and each including companion gripping elements, reversible drive mechanism for operating said rolls and periodically reciprocating said heads and spaced devices engaging periodically with said gripping elements for shifting the same laterally in their movement towards and away from said rolls for turning work carried thereby and means capable of bodily shifting the heads laterally in relation to the said rolls.

35. A fiber tube rolling machine comprising a frame, rolls carried thereby, driving mechanism therefor, a pair of tube engaging heads slidably mounted on said frame and each including a pair of companion work-gripping elements, reversing mechanism for operating said rolls, means for periodically connecting said heads to said driving mechanism for the reciprocation thereof, and cam devices supported by said frame for periodic engagement with said heads for shifting said elements relative to each other.

36. A fiber tube rolling machine comprising a frame, rolls carried thereby, driving mechanism therefor, a pair of tube engaging heads slidably mounted on said frame, reversing mechanism for operating said rolls, means for periodically connecting said heads to said driving mechanism for the reciprocation thereof, cam devices supported by said frame for periodic engagement with said heads for shifting said heads relative to each other, and means for displacing a head laterally with relation to the rolls when the heads reach a predetermined position in relation to the rolls.

37. A fiber tube rolling machine comprising a frame, a pair of companion rolls mounted upon said frame and provided with tube receiving grooves, a pair of tube engaging heads slidably mounted on said frame for movements toward and away from said rolls and each consisting of companion gripping elements for engagement with the tubes, a drive mechanism for the rolls and heads, cams positioned along said frame for periodic engagement with said heads for shifting said elements in relation to each other, a weight gravitating into position to shift one of said heads horizontally in relation to said grooves, and mechanism for releasing said weight when the heads have travelled a predetermined distance.

38. A fiber tube rolling machine comprising a tube rolling device, companion feeding mechanisms positioned on opposite sides of said rolling device for feeding tubes to said device, shifting means for shifting said mechanism laterally with relation to said rolling device, drive mechanism for operating said feeding mechanisms toward and away from said device, and means periodically operating in the movements of said feed mechanisms for controlling the operation of said shifting means.

39. A fiber tube rolling machine comprising a tube rolling device, companion feeding mecha-

- nisms for feeding tubes to said device, shifting means for shifting said mechanisms laterally with relation to said rolling device, drive mechanism for operating said feeding mechanisms toward and away from said device, means periodically operating in the movements of said feed mechanisms for controlling the operation of said shifting means, and means for giving a partial turn to the tubes after the lateral shifting thereof.
40. A fiber tube rolling machine comprising a tube rolling device, companion feeding mechanisms, for feeding tubes to said device, shifting means for shifting said mechanisms laterally with relation to said rolling device, drive mechanism for operating said feeding mechanisms toward and away from said device, means periodically operating in the movements of said feed mechanisms for controlling the operation of said shifting means, means for giving a partial turn to the tubes after the lateral shifting thereof, said rolling device discharging the tubes from the machine as finished.
41. A rolling machine comprising a supporting frame, rolling mechanism mounted thereon, reversible drive mechanism for the rolling mechanism, duplex feeding mechanisms operated by said drive mechanism for travel in opposite directions for feeding material back and forth through said rolling mechanism and automatic means for periodically reversing said drive mechanism.
42. A rolling machine comprising a pair of rolls having on their peripheral surface matching groups of longitudinally aligned grooves, mechanism for selectively and progressively feeding material from the first groove to the last groove of said group of grooves and mechanism for periodically moving said mechanism in opposite directions.
43. A rolling machine comprising rolling mechanism, horizontally aligning duplex material feeding mechanisms on opposite sides of said rolling mechanism including companion grippers for gripping material and means for changing the gripping relation between the grippers and the material and thereby change the surface contact between the rolling mechanism and the material feeding therethrough.
44. A rolling machine comprising rolling mechanism, horizontally aligning duplex feeding mechanisms on opposite sides of said rolling mechanism including companion grippers for gripping material and feeding same through said rolling mechanism, operating mechanism operating on said grippers to shift the same laterally for changing the aligning position of the material with the rolling mechanism and means for reciprocating said feeding mechanisms.
45. A rolling machine comprising a pair of rolls, a pair of companion slidably mounted feeding mechanisms associated therewith, and a single drive mechanism periodically engaging said feed mechanisms to individually slide the same according to the direction of travel of said rolls.
46. A rolling machine comprising a pair of rolls, a pair of companion feed mechanisms associated therewith, and a single drive mechanism periodically engaging said feed mechanism to slide the same according to the direction of travel of said rolls for reciprocating materials back and forth through said rolls and capable of progressively shifting the material longitudinally of the rolls and to periodically discharge the material from the rolls.
47. A rolling machine comprising a pair of rolls, a pair of companion feed mechanisms associated therewith, drive mechanism periodically engaging said feed mechanisms to slide the same according to the direction of travel of said rolls for reciprocating materials back and forth through said rolls and capable of progressively shifting the material longitudinally of the rolls and to periodically discharge the material from the rolls, and reversing mechanism for driving said feed mechanisms.
48. A rolling machine comprising rolling mechanism, a reversible drive mechanism therefor, a pair of companion feeding heads for feeding material back and forth through said rolling mechanism and having operative connection with said reversible drive mechanism and a control connection between said heads and said reversible drive mechanism whereby the drive mechanism is reversed in the movements of the heads towards and away from the rolling mechanism.
49. A rolling machine comprising rolling mechanism, a reversible drive mechanism therefor, a pair of companion feeding heads for feeding material back and forth through said rolling mechanism and having operative connection with said reversible drive mechanism and a control connection between said heads and said reversible drive mechanism whereby the drive mechanism is reversed in the movements of the heads towards and away from the rolling mechanism and means positioned to laterally displace the heads when reaching a predetermined relation with the rolling mechanism for shifting the material laterally in relation to the travel of the heads.
50. A rolling machine comprising a pair of rolls, reversible drive mechanism therefor, a pair of material supporting heads operated directly off said driving mechanism for movements towards and away from said rolls and positioned at opposite sides of the rolls.
51. A rolling mechanism comprising a pair of rolls, reversible drive mechanism therefor, a pair of material supporting heads operated directly off said drive mechanism for movements towards and away from said roll and control mechanism whereby the direction of travel of said drive mechanism may be changed according to the position of said heads.
52. A rolling machine comprising a pair of rolls, reversible drive mechanism therefor, a pair of material supporting heads operated directly off said drive mechanism for movements towards and away from said rolls and control mechanism whereby the direction of travel of said drive mechanism may be changed according to the position of said heads, and means for shifting the heads laterally in relation to the path of travel thereof and according to the positions of the heads.
53. A fiber tube rolling machine comprising a pair of rolls, a pair of slidably mounted heads for feeding work toward and away from said rolls, drive mechanism for reversibly driving said rolls and periodically sliding said heads, a control device set into operation according to the position of said heads for reversing the direction of travel of said drive mechanism, and means for shifting one of said heads in a direction longitudinally of said rolls at predetermined points in the travel of said heads.
54. A fiber tube rolling machine comprising a frame, a pair of rolls supported thereby, a pair of tube engaging heads slidably mounted on said frame and each including a pair of companion

work gripping elements, reversing mechanism for operating said rolls, means for periodically connecting said heads to said driving mechanism for the reciprocation thereof, and cam devices supported by said frame for periodic engagement with said heads for shifting said elements relative to each other.

5 55. A fiber tube rolling machine comprising a frame, a pair of rolls supported thereby, a pair of tube engaging heads slidably mounted on said frame, reversing mechanism for operating said rolls, means for periodically connecting said heads to said driving mechanism for the reciprocation thereof, cam devices supported by said frame for periodic engagement with said heads for shifting said elements relative to each other, and means for displacing a head laterally with relation to the rolls when the heads reach a predetermined position in relation to the rolls.

10 56. A fiber tube rolling machine comprising a tube rolling device companion feed mechanisms for feeding tubes to said device, shifting means for shifting said mechanisms laterally with relation to said rolling device, drive mechanism for operating said feeding mechanisms toward and away from said device, and means periodically operating in the movements of said feed mechanisms for controlling the operation of said shifting means.

15 57. A rolling machine comprising a pair of companion rolls, a supporting frame including a pair of horizontally spaced rods, a pair of companion work supporting heads slidably mounted on said rods to the opposite sides of said rolls, cam devices arranged at the ends of travel of said heads for shifting the heads laterally of said rods, a rack bar, means for periodically connecting and disconnecting the heads

from said rack bar and mechanism for operating said bar.

5 58. A rolling machine comprising a pair of companion rolls, a supporting frame including a pair of horizontally spaced rods, a pair of companion work supporting heads slidably mounted on said rods to the opposite sides of said rolls, cam devices arranged at the ends of travel of said heads for shifting the heads laterally of said rods, a rack bar, means for periodically connecting and disconnecting the heads from said rack bar and mechanism for operating said bar, said mechanism including reversible gear drives and a control device between said devices and said rack bar whereby said gear devices may be manipulated according to the traveling position of said rack bar.

10 59. A rolling machine comprising a supporting frame, a pair of rolls mounted thereon, a pair of horizontally extending spaced rods 20 mounted on said supporting frame, a pair of heads one on each side of the rolls and slidably mounted on said rods, shifting devices supported by said rods at opposite ends of travel of each head for shifting the head laterally when reaching either one of its two extreme positions, a rack bar slidably supported by the frame, devices for periodically connecting the heads to the rack bar according to position of the latter, reversible mechanism for operating said rolls, a 25 drive connection between the rolls and said rack bar, a clutch rod, devices for periodically connecting the clutch rod to the rack bar and a connection between the clutch rod and said reversing mechanism whereby said mechanism may be 30 reversed according to the position of said rack bar.
